POLISHING MACHINE

Charles G. Schenk, New Britain, Conn., assignor
to The Fafnir Bearing Company, New Britain,
Conn., a corporation

Application July 1, 1949, Serial No. 102,611

6 Claims. (Cl. 51—145)

1

My invention relates to a polishing machine, and in particular to a machine for automatically finish-polishing race grooves of the inner rings of antifriction bearings.

It is an object to provide an improved device of the character indicated.

It is another object to provide a machine for simultaneously polishing a plurality of antifriction-bearing race grooves at one time.

It is a further object to provide an improved finish-polishing machine, wherein an automatically performed polishing operation may consistently and uniformly finish-polish a plurality of successively chucked and a plurality of simultaneously chucked pieces of work.

It is also an object to provide an improved automatic polishing machine wherein the cycle of operation may be reduced to a minimum.

It is still another object to provide an improved machine of the character indicated wherein an accurately controlled rough-polishing operation and an accurately controlled finish-polishing operation may be automatically performed on the same work in a single cycle of operation.

Other objects and various further features of the invention will be pointed out or will occur to those skilled in the art from a reading of the following specification in conjunction with the accompanying drawings. In said drawings, which show, for illustrative purposes only, a preferred form of the invention:

Fig. 1 is a plan view of a machine incorporating features of the invention and shown with certain parts broken away and in section, the mechanism being in the polishing position;

Fig. 2 is a sectional view taken more or less in the planes of the line 2—2 of Fig. 1 and showing a side elevation of a subassembly of the machine of Fig. 1, parts of the mechanism being retracted away from the polishing position;

Fig. 3 is a view in side elevation of a part of the mechanism of Fig. 1;

Fig. 4 is an enlarged fragmentary view in partial section of chucking means in the machine of Fig. 1; and

Fig. 5 is an electric-wiring diagram schematically illustrating an interconnection of elements in the machine of Fig. 1.

Briefly stated, my invention in a preferred form contemplates an improved means for bringing a polishing belt into operating relation with an article to be polished. The article to be polished may be revolubly mounted on a spindle which may rotate at relatively high speed, while the polishing belt may be driven at a relatively low speed. In the form to be described, I provide means whereby a plurality of polishing operations may be simultaneously performed with uniform accuracy. My machine may be automatic in its operation and may be readily adapted to or set up for the rough polishing and/or for the

finish polishing of a number of different types and sizes of articles to be polished. In the form to be described, abrasive may be uniformly applied to the polishing means and the timing for such application may be closely controlled.

Referring to the drawings, my invention is shown in application to an automatic polishing machine for finish-polishing the ball-race grooves 10 of a plurality of rings 11, which may be the inner rings of antifriction bearings. The rings 11 may be mounted in end-to-end axial adjacency for rotation with a spindle 12, shown supported in spaced pillow blocks 13. The spindle 12 may be driven at relatively high speed by a motor 14 connected as by a belt 15 between pulleys 16—17.

The polishing means for the race grooves 10 may be a single length of belting or cord laid in multiple loops between a plurality of drive pulleys or sheaves 18 and a plurality of idler pulleys or sheaves 19, but in the form shown I employ a separate polishing belt or cord 20 stretched between each pair of pulleys 18—19. The polishing belts 20 may obtain their drive from the same drive means as the spindle 12, but, in the form shown, I have employed a second motor 21 with suitable reduction-gearing means 22 to drive the drive sheaves 18.

In accordance with the invention, the polishing belt or belts 20 may be automatically advanced to and retracted from a polishing engagement with the work 11 supported on the spindle 12; and, in the form shown, I achieve this relative movement by mounting the entire assembly of polishing means within one framework, which is movable relatively to the framework which supports the spindle 12 and its drive means. Thus, the spindle 12 and the motor 14 may be relatively fixedly mounted upon a base member or frame 23, while the polishing assembly may be mounted upon a frame-plate member 24 that is displaceable relatively to the frame 23. Also in accordance with a feature of the invention, I provide means for angular adjustment of the inclination of that part of the polishing belt or belts 20 which is to engage the work.

To achieve advancing and retracting sliding movement, the frame 24 may be slidably guided between dovetail rails or guides 25 which may be formed in or secured to a mounting or base-plate member 26. In order to permit the desired angular adjustment, the base plate 26 may in turn be transversely slotted, as at 27, at the locations for securing the base plate 26, as by means of tightening bolts 28. For a purpose which will later be clear, I also prefer that the base plate 26 shall be longitudinally adjustable with respect to the axis of spindle 12, and I have therefore included longitudinal guide means 29 as a part of the main supporting framework 23.

Advancing and retracting movement of the

polishing assembly may be governed by a fluid-pressure operated means in the form of a double-acting cylinder 30, shown mounted on a bracket 31 carried by the longitudinally and angularly adjustable base plate 26. The actuating means 30 is shown to include a stem 32 locked to the carriage 24 for the polishing means.

As explained, all polishing means in the form shown is carried by the carriage 24. The idler pulleys or sheaves 19 may, therefore, be supported by bracket means 33 vertically adjustably mounted, as at 34 (Fig. 2), on a bracket 35 carried by or forming part of the displaceable carriage 24. The sheaves 19 may be of a plurality appropriate to the number of race grooves 10 to 15 to be polished, and, therefore, the mounting stud or arbor 36 on the bracket 33 may be of a length to accommodate a desired number and spacing of sheaves 19. A readily accessible securing nut 37 may permit removal and substitution of idler 20 sheaves 19. In like manner, the drive shaft 38 to be driven by the reduction-gear means 22 may also be of sufficient length to accommodate a desired number and spacing of sheaves 18, and the assembly of these drive sheaves 18 may be 25 secured by a readily accessible nut 39.

In order that all belts 20 shall perform uniform polishing operations on the various race grooves 10, I provide belt-tensioning means for each belt 20, and means for equalizing the tensioning forces applied to each belt 20. The various tensioning means may all be supported by a bracket 40 adjustably mounted on the bracket 33, and each tensioning system may utilize an idler roller 41 supported by the stem of a fluid-pressure actuated means 42. The various fluid-pressure actuated means may all be manifolded, as at 43, and the pressure within the manifold may be maintained, as by connection at 44 to a source of fluid pressure. In the form shown, the various fluid-pressure actuators 42 for the belt-tensioning means are longitudinally adjustable, as in slots 45 along the bracket 40, in order that the tensioning elements may be positioned in true-running relation with the particular belt 20 to be tensioned, as will be clear.

In accordance with a further feature of the invention, I provide means for application of abrasive to the belt or belts 20 as desired, and the application to all belts 20 may be uniform. The application means may comprise a longitudinally extending wetting roller 47 rotatably supported between spaced arms 48 of a rockable assembly, pivoted as at 49 to the frame 24. The roller 47 may be partially immersed in a reservoir or pan 50 containing a solution or suspension of abrasive. The supporting yoke 48 for the roller 47 may be normally spring-urged (as by a tension spring 51 acting on a crank 52) in a downward direction, that is, in a direction away from 60 contact with the belts 20. However, upon actuation by means of a solenoid 53, a crank extension 54 of the yoke 48 may be displaced to set the wetting roller 47 in abrasive-applying contact with the belts 20. In the form shown, the armature of solenoid 53 is connected by two links to the crank arm 54, and the upper link 55 may be adjustably secured, as by tightening a nut 56, in order to provide a selected application force 65 for the roller 47 against the belts 20.

In order that the cycle of operations of my machine may be reduced to a minimum, I provide braking means for quickly arresting rotation of the spindle 12 upon completion of a polishing operation. Such braking means may be solenoid 75

actuated, and in the form shown I have employed internally expanding brake shoes 58 within the drive pulley 16 (see Fig. 3). The brake shoes 58 may each carry actuating pins 59 normally urged toward each other by means of a spring 60 and positioned to be spread apart and into braking contact with the pulley 16 upon actuation of a solenoid 61. The armature of solenoid 61 may lift a cam or wedge member 62 to spread the shoes 58, as will be clear.

I have explained that my machine is applicable to the simultaneous finish polishing of a desired plurality and spacing of inner race grooves, such as the grooves 10 of inner bearing rings 11. The supporting means for such a plurality of rings may include a chuck which may permit fast loading and unloading of unfinished and finished parts. In Fig. 4, it will be seen that such chucking means may include a mandrel 65 upon which the pieces of work 11 are to be supported. The mandrel 65 may include an enlarged base or flanged portion 66 to be secured, as by bolts 67, to a flanged member 68 which may be threaded on the end of the spindle 12. A chucking stem 69 may be longitudinally slidable within the mandrel 65 and be normally urged to the right (in the sense of Fig. 4) by spring means 70 within the flanged member 68. Spring action may be adjustably selected by means of a nut 71 threaded on the end of the stem 69 to receive abutment of the spring 70. The outer exposed end of stem 69 may be recessed to receive a C-washer 72, to be urged by spring 70 into compressional abutment with the work sample at the outer end of the mandrel 65.

In an unchucking operation, an actuating rod 73 may be shifted by a manually actuated system including a crank 74 operating an eccentric 75. The eccentric may be connected to a crank 76, pivoted as at 77 to the frame 23, and the crank 76, when actuated clockwise in the sense of Fig. 1, may longitudinally displace the actuating rod 73 against the action of spring 70. In order to provide minimum wear between the crank 76 and the actuating rod 73 (which may rotate with the spindle 12), I provide antifriction thrust-bearing means 78 at the point of engagement between crank 76 and the actuator means 73. A turnbuckle 79 between the eccentric 75 and the crank 76 may serve for adjustment of the described chucking means, so as to provide a desired throw of the actuating rod 73 for each throw of eccentric 75. It will be clear that when the eccentric 75 is thrown in an unclutching operation, the stem 69 may be projected outwardly so as to free the C-washer 72 from abutment with the outer work sample 11. The C-washer may then be manually removed so as to free all the work samples.

A better understanding of my machine may be had from a description of a typical cycle of operation, utilizing electrically interlocked controls, as shown schematically in Fig. 5. In the arrangement of Fig. 5, all relays and solenoids, 65 and both motors 14-21 are connected to the same source of electrical supply. In particular, a double-pole switch 85 may apply line voltage across the normally open contacts of motor-starting relays 36-37 in readiness for a relay-70 operated starting of the motors; likewise, a double-pole switch 88 may supply line voltage for operation of the various relays and solenoids. It will be noted, however, that when the switch 88 is thrown, brake solenoid 61 is the only solenoid 75 to be energized so that, in the starting position

5

(with the polishing carriage 24 retracted), the brake 58 is set against the drum of pulley 16 to hold the spindle 12 at rest.

In the system of control shown, I employ two time-delay relays 89-90, first, to permit selected determination of the period during which abrasive should be applied to the polishing means (rough polishing) and, second, to determine the period of subsequent polishing without abrasive (finish polishing). Both relays 89-90 are shown 10 to include normally closed contacts, that is, contacts which will remain closed and which will not be opened until after the lapse of the selected time, following an energizing of the delay mechanism. Such delay relays are well known in the art and, therefore, will not be illustrated or described in detail herein. It will be noted that when the main switch 88 is closed, the brake solenoid 61 is energized by way of the normally closed contacts of delay relay 90 and by way of 20 a double-pole double-throw relay 91, which relay 91 will be in the dropped or lower position before the cycle of operation is initiated.

To initiate the cycle of operation, the starter button 92 of a start-stop assembly 93 may be 25 pushed to close a circuit to the delay relays 89-90, thereby initiating the selected timing intervals for each of these relays 89-90; at the same time, the coil of the double-pole double-throw relay 91 may be energized to operate the starting relays 86-87 for both motors 14-21 and to energize the solenoid 94, which may position the selector valve 95 for an advancing movement of the advancing-and-retracting means 39-32. A push of the starter button 92 may 35 thus effectively simultaneously commence rotation of the spindle 12 and of the polishing means 20 while dropping out the brake solenoid 61 in order to release the brake. At the same time, the polishing carriage 24 may be projected into 40 working position.

Now, when the double-pole double-throw relay 91 was energized to establish connections in the up-position, line voltage was also applied across a normally open limit switch 96 in series with the abrasive-applying solenoid 53. In Fig. 2, it will be seen that the limit switch 96 may be fixedly mounted upon the polishing base plate 26, and its follower roller 97 may be poised to intercept a part of the polishing carriage or a part carried thereby as said carriage is forwardly projected into work position. In the form shown, the follower roller 97 for the limit switch 96 may be depressed as it rides under the bottom of the abrasive-solution reservoir 50, as will be clear. Thus, just as the polishing means 20 is about to engage or engages the work 11, the solenoid 53 may be energized so as to apply abrasive to the polishing means 20.

With the operations thus far described, it will be appreciated that both delay periods have commenced to run and that abrasive or rough polishing has been commenced merely upon depression of the starter button 92. If desired, the starter button may be released and the starting circuit effectively maintained closed by means of a holding coil, but in the form shown, I have employed a second switch 98 having normally open contacts to be closed when the follower roll 99 thereof intercepts the reservoir pan 50 in a projected or advanced or working position of the polishing means. If it is desired to have an interval of polishing without abrasive (finish-polishing interval) after a given interval of polishing with abrasive (rough-polishing interval), the delay 70

6

relay 89 may be set to operate prior to operation of the delay relay 90. In that event, i. e. at the end of the rough-polishing interval, operation of delay relay 89 may serve to open the contacts thereof and thereby to break the circuit to the abrasive solenoid 53, thus allowing spring 51 to retract the abrasive or wetting drum 47 from contact with the polishing means 20. It will be clear that polishing will then proceed without abrasive.

After the lapse of the selected period of polishing without abrasive (finish-polishing interval), the delay relay 90 will operate to open its contacts and thereby to interrupt the circuit to the coil of the double-pole double-throw relay 91. Relay 91 may then substantially immediately drop out so as to deenergize the motors 14-21 and to deenergize the valve-positioning solenoid 94. A spring 94' associated with the solenoid 94 may return the selector valve 95 to a position calling for retraction of the polishing carriage. Concurrently with the deenergizing of the electric motors 14-21 and when the relay 91 falls to its down position, the circuit to the braking solenoid 61 will again be established so that the spindle 12 may be brought to a halt virtually immediately and with the polishing means 20 out of contact with the work 11. It will be appreciated that when the polishing carriage 24 is retracted, both limit switches 93-98 will be returned to their normally open condition; in the case of the switch 98, the opening of contacts may deenergize both delay relays 89-90, thus permitting return of the contacts thereof to their normally closed state in readiness for another start-button-initiated cycle of operation.

If for some reason during the cycle of operation it should be desired to stop my machine, a depression of the stop button 100 will immediately serve to break circuits to the coils of relays 89-90-91, and it will be appreciated that the effect of pushing the stop button may be immediately to shut off the motors 14-21, to brake the spindle 12, and to return the polishing carriage 24 to its retracted position, thereby effectively resetting the complete mechanism in readiness for another cycle of operation.

It will be appreciated that I have described an improved polishing means having particular application to the precision polishing of ball raceways for antifriction bearings. By providing selectable delays in the relays 89-90 I may control the depth of cut produced during abrasive polishing and during non-abrasive polishing, and both 55 these cuts may be performed in quick succession with no loss of time. My machine lends itself to the simultaneous polishing and to the uniform polishing of a number of sizes and types of bearing rings; and by means of the angular adjustment feature described in connection with securing bolts 28 and slots 27, the polishing means 20 may effectively finish-polish a number of different raceway curvatures. In the particular structure to which I have applied my invention in the 60 production polishing of inner-raceway grooves, I have run the polishing belts 20 at a relatively slow speed (about 36 R. P. M.) while running the spindle 12 at a relatively high speed (about 7000 R. P. M.), depending upon the diameter to be polished. I have set the delay relay 89 to time the application of abrasive solution for the relatively short period of two seconds and have set the delay relay 90 to time the finish or non-abrasive polishing operation to run approximately 70 three seconds thereafter. A full polishing cycle

for a plurality of rings may thus be completed in substantially less than 10 seconds, as will be clear.

While I have described my invention in detail for the preferred form shown, it will be understood that modification may be made within the scope of the invention as defined in the appended claims.

I claim:

1. In a polishing machine of the character indicated, a frame, a spindle journaled for rotation on a fixed axis on said frame and including means for revolvably supporting an article to be polished, a slide guided on said frame for sliding movement generally radially of said spindle axis, polishing-belt means carried by said slide and including spaced pulleys on parallel axes substantially parallel to said spindle axis, said pulley axes being differently spaced from the plane of guided movement of said slide so that a belt stretched over said pulleys may present a free span to work supported on said spindle when said slide is advanced toward said spindle, advancing-and-retracting means for actuating said belt means into and out of polishing engagement with the article to be polished, drive means for said spindle and for said polishing-belt means, abrasive-applying means carried by said slide and independently actuatable into and out of abrasive-applying relation with said polishing-belt means, and timing means effective while said slide is in a work-engaging position to hold said abrasive-applying means in abrasive-applying position for a first interval and to hold said abrasive-applying means out of abrasive-applying relation with said polishing-belt means during a second interval, whereby said polishing-belt means may perform both rough-polishing and finish-polishing operations on the work.

2. A polishing machine according to claim 1, in which means including an element to be actuated upon a movement of said advancing-and-retracting means renders said drive means ineffective to rotate said spindle upon a retraction of said slide.

3. A polishing machine according to claim 1, in which braking means for said spindle includes an actuating element poised to interception of said slide upon a retraction of said slide.

4. In a polishing machine of the character indicated, a frame, a spindle journaled on a fixed axis on said frame and including means for revolvably supporting an article to be polished, guide means on said frame and extending generally parallel to said spindle axis, polishing means guided by said guide means and including belt means spanning spaced pulleys, said belt means being sufficiently elevated with respect to said guide means and said spindle axis that a free length of the belt is poised for polishing contact with the article to be polished, drive means for said spindle and for said polishing means and connected to produce simultaneous relative movements of said polishing means and of the article to be polished at the location of polishing contact, advancing-and-retracting means for actuating said slide to move the free length of said belt means generally radially towards and away from polishing engagement, abrasive-applying means for said polishing means and including a member actuatable independently of said advancing-and-retracting means, disconnecting means for disconnecting said drive means from said spindle, brake means for braking said spindle, and timing means including an element positioned for

actuation upon a movement of said advancing-and-retracting means to apply said abrasive-applying means to said polishing means for a first selected timing interval and to retract said abrasive-applying means from said polishing means for a second timing interval and to retract said advancing-and-retracting means upon completion of said second timing interval, said disconnecting means and said brake means being operative upon conclusion of said second timing interval.

5. A polishing machine according to claim 4, in which said polishing means includes a first plurality of pulleys on a first axis substantially parallel to said spindle axis, and a second plurality of pulleys spaced from said first plurality on an axis parallel to the axis of said first plurality, belt means spanning said pulleys, whereby between each corresponding pair of pulleys on said pulley axes there may be a first free belt span for polishing contact with the article to be polished and a second free belt span, and fluid-pressure preloaded tensioners for each such second belt span, said tensioners being in fluid communication with each other, whereby all belt tensioners may be uniformly preloaded so that a plurality of concurrent polishing operations may be uniformly performed.

6. In a polishing machine of the character indicated, a spindle with means for revolvably supporting an inner bearing ring with a concave race groove to be polished, polishing means including mounting means supporting spaced pulleys on parallel axes that are substantially parallel to the axis of said spindle, and a belt supported by said pulleys for polishing contact of one span thereof with the bearing race groove to be polished, means for moving said mounting means generally radially toward and away from said spindle, abrasive-applying means actuatable into and out of abrasive-applying relation with said polishing means, and angular-adjustment means effective between said spindle and said polishing means, whereby the axes of said spindle and of said polishing means may be inclined relatively to each other to produce a polishing contact of said belt with the bearing-race groove at an angle to the radial plane of symmetry of the race groove.

CHARLES G. SCHENK.
